Inventor:

Joseph A. Wilson.

UNITED STATES PATENT OFFICE.

JOSEPH A. WILSON, OF CHESTER, VERMONT.

SADDLE-BOARD.

SPECIFICATION forming part of Letters Patent No. 295,847, dated March 25, 1884.

Application filed July 23, 1883. (No model.)

To all whom it may concern:

Be it known that I, JOSEPH A. WILSON, a citizen of the United States, residing at Chester, in the county of Windsor and State of Vermont, have invented a new and useful Improvement 5 in Saddle-Boards, of which the following is a specification.

My improvement consists in making, of any material for buildings that are shingled with wooden shingles, a saddle - board having grooves or channels formed on its lower edges, said grooves to be filled with some known preservative of wood.

The figure in the accompanying drawing 15 gives a view in perspective of the saddle-board.

A A are the grooves to be filled.

The drawing gives such a full, clear, and exact description of the invention that others 20 skilled in the art to which it appertains can make the same.

The object of my invention is to preserve the shingles. Every time it rains a small portion of the filling will be washed onto the shingles, and they will soon become saturated 25 with the preservative.

I am aware that it has before been contemplated to preserve shingles by means of preservative substances employed in a channel or tank mounted upon top of the ridge-piece, 30 as in I. W. Dean's Patent No. 81,147, August 18, 1868. I therefore claim nothing therein shown.

What I claim, and desire to secure by Letters Patent, is—

35 The saddle - board, substantially as shown and described, having the grooves or channels formed upon its lower edges, as set forth.

JOSEPH A. WILSON.
